United States Patent Office.

SAMUEL DAVIS, OF KANSAS, MISSOURI.

Letters Patent No. 66,224, dated July 2, 1867.

IMPROVED WASHING MACHINE.

The Schedule referred to in these Letters Patent and making part of the same.

TO ALL WHOM IT MAY CONCERN:

Be it known that I, SAMUEL DAVIS, of the city of Kansas, in the county of Jackson, in the State of Missouri; have invented a new and improved Washing Machine; and I do hereby declare that the following is a full and exact description thereof, reference being had to the accompanying drawings, and to the letters of reference marked thereon.

The nature of my invention consists in the connection of a revolving plunger, so arranged and attached to a single lever as to admit of its turning by means of a swivel; and, furthermore, my invention relates to a dasher, so constructed as to cause the water to flow from the outer circle towards the centre, thereby loosening the clothes by the suction principle employed, as hereinafter described.

To enable others skilled in the art to make and use my invention, I will proceed to describe its construction and operation. And I do hereby declare that the following is a full, clear, and exact description of the construction and operation of the same, reference being had to the annexed drawings, making a part of this specification, in which—

Figure 1 is a longitudinal section, and

Figure 2 is a top view of it.

Figure 3 is a vertical and transverse section of the swivel connection of the dasher or plunger.

A represents a tub, in which works a plunger, B B, with a suction-board, O O, and an opening in the centre for the passage of water while compressing the clothes. In operating the machine, the surging motion of the water keeps the clothes loose. While the dasher is being raised, the plunger may revolve, so that a uniform bearing is effected upon all parts of the clothes. Letter F is an upright standard, secured to the plunger B B, and forming such connections as are represented by letter E, closing over by flanges the standard F. Both E and F are firmly secured together by a bolt. D is a shackle-bar, connected with E by means of a swivel, a, and upon this swivel the plunger B B may revolve. The shackle-bar D is connected to the lever C, which operates the machine. The fulcrum H secures the lever while attached to the cross-bar I, supported by stands from the outer edge of the tub A, so as to give stability and solidity to the tub A, thus giving an easy but powerful motion as applied to the clothes. This combination is so adjusted that, while throwing back the lever C, the plunger B B will drain itself in the tub A.

What I desire to secure by Letters Patent, and what I claim as my invention, is—

The combination as well as the arrangement of the annular suction-ring or board O with the perforated or grated plunger B, and the application of the plunger to its working lever C, by means of a swivel connection, in order to enable the plunger to revolve while in use, the whole being substantially as described.

SAMUEL DAVIS.
